Primary Examiner — Marissa J Cash(74) Attorney, Agent, or Firm — LADAS & PARRY LLP(57) CLAIM

The ornamental design for a confetti launcher, as shown and described.

DESCRIPTION

FIG. 1 is a perspective view of a confetti launcher showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings are for purposes of illustrating portions of the confetti launcher that form no part of the claimed design.
